ATTORNEY

UNITED STATES PATENT OFFICE.

ANDREW R. MUNRO, OF MEDICINE LAKE, MONTANA.

PAPER CAP FOR MILK-BOTTLES.

1,303,710.

Specification of Letters Patent. Patent May 13, 1919.

Application filed May 16, 1918. Serial No. 234,918.

To all whom it may concern:

Be it known that I, ANDREW R. MUNRO, a citizen of the United States, residing at Medicine Lake, in the county of Sheridan 5 and State of Montana, have invented certain new and useful Improvements in Paper Caps for Milk-Bottles, of which the following is a specification.

This invention relates to bottle closures, 10 and more particularly to the paper caps used for milk bottle closures.

The object of the invention is to provide a sanitary closure of this character constructed to render it both dust and dirt proof 15 and absolutely fluid tight to adapt the bottle equipped with it to be placed in any position without leaking.

Another object is to provide a closure of this character so constructed as to prevent 20 accumulation of extraneous matter in the mouth of the bottle above the ordinary disk closure which accumulation frequently works around the edge of the disk resulting in contamination of the milk.

Another object is to so construct the closure as to insure a clean surface on the bottle mouth over which the milk is poured.

With the foregoing and other objects in view, which will appear as the description 30 proceeds, the invention resides in the combination and arrangement of parts and in the details of construction hereinafter described and claimed, it being understood that changes in the precise embodiment of the invention herein disclosed may be made within 35 the scope of what is claimed without departing from the spirit of the invention.

In the accompanying drawings:—

Figure 1 represents a vertical section of 40 the upper portion of a milk bottle equipped with this improved closure shown in section.

Fig. 2 is a top plan view thereof, and

Fig. 3 is a bottom plan view with parts broken out.

In the embodiment illustrated, a paper disk 1 such as is ordinarily employed for closing milk bottles is shown, connected with an outer cap 2 held spaced from the inner disk or cap 1 by means of a suitable spacer 45 here shown in the form of a plurality of paper disks 4 of smaller diameter than the disk 1, which are connected between the two caps 1 and 2 by a wire bent to form a handle loop 5, the arms 8 of which pass through the 55 inner and outer caps and the spacing disks

and have their inner ends turned inwardly and clamped as shown at 9. This combined connector and handle is preferably composed of a single piece of wire bent midway its ends to form the handle loop 5, then twisted 60 as shown at 6 and extended laterally as shown at 7 with the lateral portions of arms resting on the outer face of cap 2 and then bent to form arms 8 extending at right angles to the arms 7, these arms 8 being of a 65 length corresponding to the thickness of the inner and outer caps and spacing disks as is shown clearly in Fig. 1, the inturned fingers 9 being clampingly engaged with the inner face of the disk 1. 70

The outer cap 2 has a curved peripheral flange 3 extending toward disk 1 and shaped to fit over the mouth of the bottle B so as to completely cover said mouth and protect its lip against all possibility of dirt entering and 75 working around disk 1 and also to insure a clean pouring lip for the milk.

These caps 1 and 2 as well as the disks 4 are preferably coated with paraffin in the usual manner to render them liquid proof, 80 although they need not necessarily be so treated.

In the use of this closure, the disk 1 is inserted in the mouth of the bottle in the usual manner and the outer cap 2 fits down 85 over the rim of the bottle mouth, the flange 3 thereof extending some distance over said mouth as is shown clearly in Fig. 1.

By forming the spacing disks 4 of less diameter than the inner disk 1, an air space 90 is formed around said spacing disks between the inner and outer caps when the device is applied as shown in Fig. 1, which assists in retaining the closure in operative position.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the claimed invention. 95

Having thus fully described my invention, what I claim as new and desire to secure by Letters Patent, is:—

A bottle closure comprising a flat disk-like member to fit within the bottle mouth, an outer disk of a size to fit over the bottle mouth and to extend over and completely 110

cover said lip, spacing disks between said members, and a wire bent midway its ends to form a loop and twisted together at one side of said loop, then bent laterally out-
ward to form arms for engaging the outer face of the outer disk, said arms being bent at right angles and passed through the disks and clamped against the inner face of the

inner disk with the loop extended outwardly to form a handle.

In testimony whereof I affix my signature in presence of two witnesses.

ANDREW R. MUNRO.
